UNITED STATES PATENT OFFICE.

WALTER CHARLES TROUT, OF LUFKIN, TEXAS.

COUNTERBALANCE FOR CRANK SHAFTS.

Application filed October 12, 1925. Serial No. 61,977.

My invention relates to a counter balance for use on a crank shaft. It is particularly adaptable for use on pumping rigs for deep wells.

5 It is the purpose of my invention to provide a means for counter-balancing the weight of the pump rod in the pumping of deep wells; and to so construct the device that it may be applied to the crank employed in operating the walking beam, jack, or other pump rod reciprocating means. It is also desired to make the counter-balance adjustable so as to adapt it for use in balancing the weight of different loads.

10 Referring to the drawing herewith, Fig. 1 shows a side view, partly in elevation, of a crank arm embodying my invention, certain parts being broken away for greater clearness. Fig. 2 is a top plan view thereof. Fig. 3 is a side elevation of a pumping unit illustrating the use of my invention. Fig. 4 is a transverse section on the line 4—4 of Fig. 1. Like numerals of reference designate like parts in all the views.

15 I have illustrated my invention as applied to a standard pumping unit but it is to be understood as adaptable for other uses. The pump rod 1, having the load of the plunger and the fluid thereon, is reciprocated through the walking beam 2, the pitman 3, and crank arm 4, secured upon the crank shaft 5. The crank shaft may be rotated through a band wheel 6, as shown.

20 The weight of the pump rod and its load resists the rotation of the crank arm on the up stroke of the rod and assists the rotation of said crank arm on the down stroke. The result is a jerking motion upon the installation when the pump rod drops. To overcome this, I form the crank arm so as to accommodate a weight 7, adjustable along said arm, to counterbalance the weight of the rod and its load.

25 The crank arm has an opening 8 therein to fit about the shaft 5, said opening being formed along the axial center of the arm and at a point thereon spaced from the inner end 9, but at a greater distance from the outer end 10, thus forming a short inner arm and a long outer arm. The longer arm has spaced openings 12 therein for attachment to the wrist pin of the pitman 3.

30 The crank arm has its upper and lower sides formed with longitudinal mortices 13, the inner troughs of which are undercut, as shown in Fig. 4. These mortices are

closed at both ends and the ends of the arm are extended outwardly away from the same to form flanges or stops 14 and 15. The groove of the mortice also has a wide mouth 16 cut therein intermediate the ends to admit the heads 17 of the bolts 18, by means of which the weights 7 are secured to the arm.

35 The weights 7 are preferably flattened heavy plates of approximately the same thickness as the arm, one end 19 of each weight is extended and bored to form an opening to receive the bolt 18; the other end of the weights is recessed and formed with an opening to receive the other bolt 18. There are nuts on each bolt so that the weights may be clamped in any adjusted position along the arm. It will be noted that the heads of bolts 18 may be inserted 40 into the slot through the opening or mouth 16 and adjusted to the desired position and the weight may then be secured thereto. The weight may then be adjusted to any desired position and the nuts tightened to clamp the weight in that position. There are two weights 7 shown, although but one may be employed, if desired. The weights may be placed at the extreme end of the arm 4 when the weight of a heavy load is to be balanced. If a small load is being handled the weights may be adjusted to a point nearer the shaft. When no weight is on the beam the weights may be moved to be in a line on each side of the shaft as shown 45 in dotted lines in Fig. 1. This is desirable when the device is employed to raise rods from the well for repairs, or for running when the pitman is detached.

50 The placing of the counter weight upon the crank shaft in such manner that it may be adjusted to any desired position is of marked advantage and makes it possible to operate the pump with a minimum of vibration and shock which would result from an otherwise unbalanced action of the pump rod. The weights are readily attached and adjusted and may be removed without difficulty.

55 What I claim as new and desire to protect by Letters Patent is:

1. In a device of the character described, a crank shaft, means to rotate said shaft, a crank arm on said shaft extending unequal distances each side thereof to form long and short arms, a wrist pin adjustable along said long arm, said crank having oppo-

- site undercut mortices, bolts having heads
slidable in said mortices and weights secured
on said bolts to be thereby clamped in any
desired position along said crank arm.
5. 2. In a device of the character described,
a crank shaft, a crank arm thereon having
a morticed groove cut therein, said groove
being closed at the ends thereof, but having
a mouth therein between its ends, bolts hav-
10 ing their heads slideable in said groove, and
a weight on said bolts and adjustable to
desired positions along said arm in the
manner described.
3. In a device of the character described,
15 a crank shaft, a crank arm thereon having
mortices cut on its forward and rear sides,
weights slideable along said mortices and
means to clamp said weights at various ad-
justed positions along said arm to a position
on opposite sides of said shaft. 20
4. In a device of the character described, a
crank shaft, a crank arm on said shaft,
a wrist pin adjustable along said arm, said
arm having undercut mortices on its for-
ward and rearward sides, bolts having heads
25 slideable in said grooves, and weights on
said bolts adapted to be clamped thereby
at desired positions along said crank arm
for the purpose described. 25

In testimony whereof I hereunto affix my 20
signature this 5th day of October, A. D.
1925.

WALTER CHARLES TROUT.
